J. W. D. COOK.

PIPE WRENCH.

APPLICATION FILED FEB. 12, 1920.

Patented Aug. 22, 1922.

UNITED STATES PATENT OFFICE.

JOHN WILLIAM DONALD COOK, OF LONDON, ENGLAND.

PIPE WRENCH.

1,426,362.

Specification of Letters Patent. Patented Aug. 22, 1922.

Application filed February 12, 1920. Serial No. 358,180.

To all whom it may concern:

Be it known that I, JOHN WILLIAM DONALD COOK, a subject of the King of England, and residing at London, England, 5 have invented certain new and useful Improvements in Pipe Wrenches, of which the following is a specification.

This invention relates to pipe-wrenches or pipe-grips of the type in which one member having an arcuate jaw is adjustable upon 10 the second member upon which its pivots in the act of gripping the pipe or similar object. The two members are usually connected by a screw-threaded pin which 15 passes through any one of a series of holes in the shank of the second member, so that the initial opening of the jaws may be regulated according to the diameter of the pipe.

The objects of the present invention are to 20 construct an improved wrench of this character, in which the initial opening of the jaws is readily adjustable without removing the pivot pin and without the use of springs, to provide a finer adjustment than 25 in previous tools of this kind, and to attain these ends without having any parts detachably connected and therefore liable to become separated and lost or mislaid.

According to the present invention, the 30 pivot carrying member is provided with a guide having an angular face towards the shank of the inner wrench member, which latter can slide freely within the outer wrench member and between the pivot pin 35 and the guide, when brought to a position in which its edge is parallel or substantially parallel with the angular face of the guide. Preferably the two members of the wrench are pivotally connected by means of a pin 40 which passes through the arcuate jaw member, and bears upon the back edge of the shank of the second member, this edge being provided with a series of part-circular notches in which the pivot pin may be engaged. A guide for the front edge of this 45 shank is provided upon the arcuate jaw, the guide having angular faces so shaped as to maintain the pivot pin in engagement with its notch and prevent slipping when the 50 wrench is in the operative position, but adapted upon further opening of the wrench to allow the front edge of the shank of the second member to disengage its notched edge from the pivot pin. In this position the shank 55 of the second member may be moved freely up and down in relation to the arcuate jaw

member and the opening of the jaws adjusted approximately to fit the required diameter of the pipe or the like.

The invention is hereafter described 60 with reference to the accompanying drawings, in which:

Figure 1 is a elevation of an improved pipe-wrench constructed in accordance with the present invention. 65

Figure 2 is a similar view in part section of the wrench in the adjusting position.

Figure 3 is a cross-section on line 3—3 of Figure 1.

Figure 4 is a detail of a modified construction. 70

Figure 5 is a fragmental sectional view of the wrench showing the means for maintaining the shank within the handle.

The wrench comprises an inner member 75 *a* having a square jaw *b* and a shank *c* which is adapted to slide through the outer member *d*, the latter being preferably formed of a metal plate bent or stamped to a U-section, and the upper end being provided with an 80 arcuate gripping surface *e*. This jaw is reinforced by a metal block *f* secured by rivets *g*.

The shank *c* is pivotally connected to the outer member or handle *d* by means of a 85 pin *h* which may be freely slideable in holes *h'* in the handle, the ends of the pin being enlarged to prevent its falling out of position. The back edge of the shank *c* is notched at suitable intervals, the notches *c'* 90 being preferably of semi-circular shape to fit the pivot pin *h*.

Below the last notch the shank may be widened out as at *c''*, so that a shoulder is formed to prevent disconnection of the 95 parts, as clearly shown in Figure 5.

The block *f* has a guide surface *f'* lying substantially parallel to the back of the handle *d* so as to form an abutment for the front edge of the shank *c* when the wrench 100 is closed. Below the surface *f'* the guide is angularly faced at *f''*, the extent of this face being such that in the adjusting position shown in Figure 2 the shank *c* may clear the pivot pin *h*, so that it may be moved freely 105 up and down in relation to the handle *d*. In other words, the clearance between the inner faces *f''* of the guide block and the pin *h* is only slightly greater than the width from back to front of the shank *c* of the inner 110 wrench member.

When the wrench has been adjusted to the

approximate diameter of the pipe or the like, closing pressure upon the handle and shank causes the latter to swing around the angle between the faces f' and f^2 thereby moving the pin h and one of the notches c' into engagement. Further closing of the wrench results in a pivotal movement upon the pin h and gripping of the work between the jaws in the usual manner.

10 Figure 4 shows a modification in which the guide surfaces for the front edge of the shank are provided by a series of pins or rivets f^3 against which the shank may rest in either the operative or the adjusting position. 15 Three rivets f^3 are shown by way of example, the upper and central rivet corresponding as shown by the dotted lines to the face f' and the central and lower rivets to the face f^2 , while the central rivet constitutes the fulcrum around which the shank pivots in the initial adjusting movement.

It will be noted that the pivot pin bears upon the back edge of the shank of the outer member without the aid of a spring or like 25 device, and that the inner member and the outer member of the wrench are kept in their relative positions by the angularly faced guide.

Having thus described my invention, 30 what I claim as such and desire to secure by Letters Patent is:—

1. A wrench of the character described, comprising an inner member, an outer member, a pivot pin mounted in said outer member, a square jaw upon said inner member, an arcuate jaw upon said outer member, a

shank to said inner member, said shank adapted to slide freely through said outer member in one position, and said shank having a series of notches adapted to 40 engage said pivot pin as said jaws are closed from said position, and a shoulder upon said shank, said shoulder being formed upon the rear edge below said series of notches and projecting beyond the outermost portions of said notches, to engage 45 said pivot pin for preventing complete withdrawal of said inner member from said outer member.

2. A wrench of the character described, 50 comprising an inner member, an outer member, a pivot-pin mounted in said outer member, a square jaw upon said inner member, an arcuate jaw upon said outer member, a shank to said inner member, said shank having a series of notches presented towards 55 said pivot-pin, and a guide secured within said eccentric jaw, said guide having angular faces, one of said faces permitting movement of said shank to disengage from said pivot-pin for adjustment of said inner jaw, and the other of said faces bearing upon the front edge of said shank in the closed position for maintaining said shank in engagement with said pivot-pin.

In testimony whereof I have affixed my 60 signature in presence of two witnesses.

JOHN WILLIAM DONALD COOK.
